UNITED STATES PATENT OFFICE.

ROBERT SUCZEK, OF PHILADELPHIA, PENNSYLVANIA, ASSIGNOR TO C. H. WHEELER MANUFACTURING COMPANY, OF PHILADELPHIA, PENNSYLVANIA, A CORPORATION OF PENNSYLVANIA.

METHOD OF AND APPARATUS FOR COMPRESSING FLUID.

Application filed May 13, 1921, Serial No. 469,163. Renewed May 9, 1923.

To all whom it may concern:

Be it known that I, ROBERT SUCZEK, a citizen of the Czechoslovak Republic, residing in the city and county of Philadelphia, State of Pennsylvania, have invented certain new and useful Improvements in Methods of and Apparatus for Compressing Fluid, of which the following is a specification.

10 My invention relates to a method of and apparatus for raising the pressure of or compressing elastic fluid, as gas, such as air, or vapor, such as steam, or a mixture of gas and vapor, by entraining the fluid to be compressed in a jet or jets of motive fluid, more particularly gas, vapor, or a mixture of them, the mixture of entrained and motive fluids then decreasing in velocity and increasing in pressure, as is characteristic 15 of ejectors or aspirators.

In accordance with my invention, I procure greater efficiency of operation, either in single or multiple stage ejector apparatus, in the sense that for different or varying suction pressures greater amounts of fluid to be compressed are compressed or raised to the desired pressure with less motive fluid.

20 In ejector apparatus in which the throat area of the nozzle structure is constant and in which the ratio of the throat area of the nozzle structure to the outlet area of the nozzle structure, that is, the expansion ratio of the nozzle structure, is constant, and with a given pressure of motive fluid supplied to the nozzle structure, the weight or amount of the fluid to be compressed varies in predetermined way with regard to its initial or suction pressure. Accordingly, such arrangement is most effective with a given 25 nozzle structure for a given suction pressure or initial pressure of the fluid to be compressed for compressing a maximum weight or amount of fluid. It is desirable, however, that the same ejector apparatus shall be 30 available to compress maximum weight or amount of elastic fluid with the same nozzle structure under conditions of different suction pressure or initial pressure of the fluid to be compressed.

35 For this purpose I change or vary the pressure of the motive fluid supplied to the nozzle structure, whereby greater amounts or weights of fluid may be compressed from certain suction or initial pressures with the

expenditure of no more and often less motive fluid than in the case where the motive fluid for the ejector apparatus has a substantially constant pressure.

40 My invention resides in the method and apparatus hereinafter described and claimed.

For an illustration of some of the forms my apparatus may take and for an understanding of my method, reference is to be had to the accompanying drawing, in which:

45 Fig. 1 comprises several characteristic curves indicating ejector performance.

Fig. 2 is a sectional view, partly in elevation, of ejector apparatus embodying my invention.

50 Fig. 3 is a fragmentary sectional view, on enlarged scale, of one of the motive fluid throttling devices.

55 Fig. 4 is a vertical sectional view, partly in elevation, of a modified form of apparatus embodying my invention.

60 Referring first to Fig. 1, ordinates are pounds per hour of the entrained fluid or fluid to be compressed, and abscissæ are absolute suction pressures in inches of mercury column. The curve A is a characteristic 65 of a double stage ejector apparatus which may be employed, for example, for maintaining high vacuum in a steam condenser. In the example illustrated the pressure of steam or motive fluid employed upon the 70 nozzle structure in both stages is approximately 125 pounds per square inch. From an inspection of this curve it is apparent that the curve B is the characteristic for the same ejector apparatus employing, however, 75 motive fluid or steam at 100 pounds pressure as applied to the nozzle structure of the first stage, while the steam pressure applied to the nozzle structure of the second stage is 125 pounds per square inch. C is the 80 characteristic for the case where the motive fluid or steam pressure applied to the nozzle structure of the first stage is 85 pounds per square inch, while, as before, the motive fluid applied to the nozzle structure of the 85 first stage is 125 pounds per square inch.

90 From a comparison of these characteristics A, B and C, it is apparent that while the curve A corresponds with better performance as to amount of fluid entrained and compressed at higher absolute suction pressures, the characteristics B and C show better performance in the sense that greater 95 100 105

amounts of fluid are entrained and compressed at the relatively lower suction or initial pressures of the fluid to be entrained and compressed.

5 To effect the performances illustrated by the above mentioned curves, the motive fluid pressure in the second stage may, in the example discussed, remain substantially constant, while the motive fluid pressures applied to the nozzle structure of the first stage are progressively decreased as the first stage suction pressure decreases. By so decreasing the first stage motive fluid pressures for decreased suction pressures, the efficiency of the 10 15 20 25 30 35 40 45 50 55 60 65 70 75 80 85 90 95 100 105 110 115 120 125 130 135 140 atively greater amount of air or other fluid is entrained and compressed. While with the above described operation the valve 20 of the second stage is open while the valves

5 18 and 19 are closed, the performance can be still further improved by employing in connection with the second stage the nozzles 21 and 22, which have, as regards the second stage, and as regards the over-all performance of both stages, effects similar to those above described in connection with Fig. 1. My invention is, however, of more importance in connection with the first stage, since at the discharge of the diffuser D of the first 15 stage the back pressure of the first stage varies with the load or amount of air or fluid to be entrained or compressed, while as regards the second stage the pressure at the discharge of the diffuser D¹ is generally substantially constant.

When any one of the three branches 4, 5 or 6 of the first stage structure is employed, any one of the three branches 15, 16 or 17 of the second stage structure may 25 be employed.

It will be further understood as to the first stage, and also as to the second stage, that the branches 6 and 17 may be considered by-passes for the nozzles or orifices

30 10, 11 and 21, 22. It will be understood, however, that these by-passes may be omitted, and when highest pressure is to be available upon the steam chambers 2 and 13, the nozzles 10, 11 and (or) 21, 22 may 35 be simultaneously in operation.

In general, it is preferred to employ an interstage condenser between the two stages of the ejector apparatus for condensing out from the mixture discharged from the first 40 stage all condensable vapors, as the motive steam and any condensable vapors in the entrained fluid.

When an interstage condenser is employed between the first and second stage ejectors, 45 the employment of the motive fluid pressure-changing means, particularly of the first stage ejector, is of greater advantage than when no interstage condenser is employed. This is due to the fact that when 50 an interstage condenser is employed, the pressure at the discharge of the first stage ejector varies through a greater range for given variations in the weights or amounts of fluid to be entrained and compressed.

55 Referring to Fig. 4, there is shown in the first stage an ejector E, in general of any suitable character, as a tubular ejector, and such, for example, as the ejector E of Fig. 2. In the second stage the ejector E² is 60 provided with an annular nozzle N² producing a circular sheet or jet of motive fluid which entrains the fluid discharged from the first stage ejector E, and the mixture is delivered into the surrounding annular 65 diffuser D² and delivered into the discharge

casing F, from which it is discharged through the port F¹. In this case the ejector E is provided with the branches 4, 5 and 6, as in Fig. 2.

The combination of ejector E with ejector E² is of the general character disclosed in prior Letters Patent of the United States No. 1,282,595. This combination affords a perfectly stable operation throughout great variations of load or amounts of fluid to be entrained and compressed and throughout great ranges of change of pressure in the first stage suction chamber 1. However, it is of advantage to apply to the first stage 70 ejector of such combination the means for varying the motive fluid pressure for obtaining the effects hereinbefore described.

While the second stage ejector E² of Fig. 4 is shown as supplied with motive fluid at full boiler pressure, it will be understood 85 that the motive fluid for the second stage nozzle structure N² may be similarly throttled, though in general this will not be necessary or of great advantage.

While I have in Figs. 2 and 4 shown two 90 nozzles or orifices between the steam supply and the steam chamber of each stage, it will be understood that any other suitable number of orifices may be employed.

From the foregoing description it is apparent that while the nozzle structure of ejector apparatus has constant ratio of expansion, that is, the ratio of throat area to outlet area of the nozzle structure is constant, improved performance for different 95 suction pressures is available by suitably changing the pressure of the motive fluid supplied to that nozzle structure.

While, as illustrated and preferred, orifices or nozzles are employed for effecting changes in the motive fluid pressure as applied to the nozzle structures, it will be understood that any equivalent means may be employed, as for example, valve structure, if capable of being set to predetermined positions or openings. It will be understood, of course, that the valves 7, 8, 9 and 18, 19, 20 are ordinary shut-off valves with which it is difficult or impossible to procure any 100 predetermined or proper adjustments for 105 pressure determination.

What I claim is:

1. The method of compressing elastic fluid by elastic motive fluid, which consists in expanding motive fluid into jet formation, 110 entraining thereby the fluid to be compressed, converting the velocity of the mixture into pressure, and controlling the characteristic of the operation by giving to the motive fluid in advance of the aforesaid jet formation different definite or predetermined pressures.

2. The method of compressing elastic fluid by elastic motive fluid, which consists in expanding motive fluid into jet formation, 115

- entraining thereby the fluid to be compressed, converting the velocity of the mixture into pressure, and controlling the characteristic of the operation by throttling 5 the motive fluid in advance of the aforesaid jet formation to different predetermined degrees.
3. The method of compressing elastic fluid in a plurality of stages, which consists in 10 expanding motive fluid into jet formation, entraining thereby the fluid to be compressed, converting the velocity of the mixture into pressure, giving to the motive fluid in advance of the aforesaid jet formation 15 different definite or predetermined pressures, expanding in a later stage motive fluid into jet formation, entraining fluid of the aforesaid mixture thereby, and converting velocity of the mixture into pressure.
- 20 4. The method of compressing elastic fluid in a plurality of stages, which consists in expanding motive fluid into jet formation, entraining thereby the fluid to be compressed, converting the velocity of the mixture into pressure, giving to the motive fluid in advance of the aforesaid jet formation 25 different definite or predetermined pressures, condensing the condensable component of said mixture, expanding motive fluid in a 30 second stage into jet formation, entraining thereby the uncondensed component of said mixture, and converting velocity of the mixture into pressure.
5. Ejector apparatus comprising expansion 35 nozzle structure, co-operating diffuser structure, means for conveying motive fluid to said nozzle structure, means for diminishing the pressure of said motive fluid to predetermined degree, and means for bypassing 40 said last named means.
6. Ejector apparatus comprising expansion nozzle structure, co-operating diffuser structure, and a plurality of means for reducing the pressure of the motive fluid delivered to said nozzle structure to different 45 degrees.
7. Ejector apparatus comprising expansion nozzle structure, co-operating diffuser structure, means for conveying motive fluid to 50 said nozzle structure, means for diminishing the pressure of said motive fluid to predetermined degree, means for bypassing said last named means, and valve structure for controlling said pressure diminishing 55 means.
8. Plural stage ejector apparatus comprising in each stage nozzle structure and co-operating diffuser structure, and means for throttling to predetermined degree the motive fluid delivered to the nozzle structure of 60 one of said stages.
9. Plural stage ejector apparatus comprising in each stage nozzle structure and co-operating diffuser structure, and means for 65 each stage for throttling the motive fluid delivered to the nozzle structure thereof to predetermined degree.
10. The combination with staged ejectors, of interstage condenser structure, and means for throttling to predetermined degree the motive fluid delivered to the nozzle structure of the ejector discharging into said condenser structure.
11. The combination with staged ejectors, of interstage condenser structure, means for throttling to predetermined degree the motive fluid delivered to the nozzle structure of the ejector discharging into said condenser structure, and means for throttling to predetermined degree the motive fluid delivered 75 to the nozzle structure of an ejector receiving the discharge from said condenser structure.
12. Plural stage ejector apparatus comprising a plurality of staged ejectors, interstage condenser structure, and a plurality of means for throttling to different predetermined degrees the motive fluid delivered to 80 one of said ejectors.
13. Plural stage ejector apparatus comprising a plurality of staged ejectors, interstage condenser structure, and a plurality of means for throttling to different predetermined degrees the motive fluid delivered to the nozzle structure of one of said ejectors 85 discharging into said condenser structure.
14. Ejector apparatus comprising nozzle structure, co-operating diffuser structure, means for conducting motive fluid to said ejector, and a member disposed between said means and said nozzle structure having an orifice of predetermined area for diminishing the pressure of the motive fluid delivered to 90 said nozzle structure.
15. Ejector apparatus comprising nozzle structure and cooperating diffuser structure, means for delivering motive fluid to said ejector, a plurality of throttling members having orifices of different areas, and means for connecting said orifices in operative relation with said nozzle structure.
16. The method of compressing elastic fluid in a plurality of stages, which consists in expanding motive fluid into jet formation, entraining thereby the fluid to be compressed, converting the velocity of the mixture into pressure, expanding in a later stage motive fluid into jet formation, entraining thereby fluid of the aforesaid mixture, converting velocity of the resultant mixture into 115 pressure, and changing the characteristic of operation by changing to predetermined pressure said second named motive fluid in advance of said second named jet formation.
17. The method of compressing elastic fluid in a plurality of stages, which consists in expanding motive fluid into jet formation, entraining thereby the fluid to be compressed, converting the velocity of the mixture into pressure, condensing the condens- 120
- 125
- 130

able component of said mixture, expanding motive fluid in another stage into jet formation, entraining thereby the uncondensed component of said mixture, converting the 5 velocity of the resultant mixture into pressure, and changing the characteristic of the operation by changing to predetermined pressure said second named motive fluid in advance of said second named jet formation.

10 18. The method of operating ejector apparatus utilizing expanded elastic motive fluid for compressing elastic fluid, which consists in changing to predetermined extent the pressure of the elastic fluid before expansion 15 in accord with the initial pressure of the elastic fluid to be compressed.

19. The combination with ejector apparatus comprising nozzle structure having con-

stant throat area and expansion ratio for expanding elastic motive fluid, and co-operating diffuser structure, of means for changing the operating characteristic comprising means for changing to predetermined extent the pressure of the motive fluid delivered to said nozzle structure. 20 25

20. Plural stage ejector apparatus comprising an ejector, means for changing the pressure of the elastic motive fluid delivered to said ejector from one predetermined pressure to another, and a second ejector to which 30 is delivered fluid by said first named ejector for further compression by said second ejector.

In testimony whereof I have hereunto affixed my signature this 9th day of May, 1921.

ROBERT SUCZEK.
